UNITED STATES PATENT OFFICE

144,029

DESIGN FOR A KITCHEN CABINET

Felippe A. Broadbent, Washington, D. C.

Application May 18, 1945, Serial No. 119,617

Term of patent 14 years

(Cl. D33—13)

To all whom it may concern:

Be it known that I, Felippe A. Broadbent, a citizen of the United States, residing at Washington, in the District of Columbia, have invented a new, original, and ornamental Design for a Kitchen Cabinet, of which the following is a specification, reference being had to the accompanying drawings, forming part thereof.

This application is a continuation-in-part of my application Serial No. D-118,033, filed February 19, 1945.

In the drawings:

Fig. 1 is a front elevational view of a kitchen cabinet showing my new design.

Fig. 2 is an end elevational view of the cabinet.

Fig. 3 is a perspective view.

I claim:

The ornamental design for a kitchen cabinet, as shown.

FELIPPE A. BROADBENT.
